T.D. Brown,

Rein Supporter,

№23,073.

Patented Mar 1, 1859.

UNITED STATES PATENT OFFICE.

T. D. BROWN, OF MONTVILLE, OHIO.

HARNESS ATTACHMENT FOR SUPPORTING DRIVING-LINES.

Specification of Letters Patent No. 23,073, dated March 1, 1859.

To all whom it may concern:

Be it known that I, T. D. BROWN, of Montville, in the county of Geauga and State of Ohio, have invented a new and useful Improvement, which I denominate a "Driving-Line Supporter;" and I do hereby declare that the following is a full and complete description of the same, reference being had to the accompanying drawings, in 10 which—

Figure 1 is a perspective view of the line supporter, and Fig. 2, a sectional view of parts thereof.

Like letters refer to like parts, in both 15 views.

A Fig. 1 is a metallic strap, which extends along the back strap of the harness, upon the horse's rump. This strap A, may be longer or shorter to suit the size of the 20 horse. It is represented in the drawing as broken, to show that it may be longer or shorter, as may be required. This piece is attached to the back strap, by a short pin or stud B, Fig. 2, which rises about the tenth 25 of an inch, and passes through a hole in the back strap of the harness, and is secured in that position by an iron or other metallic clasp C, Figs. 1 and 2, which is first slipped upon the back strap, with the open part beneath, and then shoved back to a position that will bring the center of 30 the clasp over the pin B. This clasp will remain firmly in its place, the pin B, acting as the tongue of a buckle, and preventing the piece A, from moving backward or forward. But it can be moved forward or 35 backward at pleasure, by shoving off the clasp from the pin, and placing the pin in another hole in the back strap, and replacing the clasp upon the pin as before.

Toward the rear end of the strap A, is riveted a cross piece D. This piece D is placed at right angles to the piece A, about two and a half inches, or three inches from 45 the back end D'. This cross piece D, together with the end D', is covered with leather, or otherwise mounted to agree in style of finish with the other parts of the harness. This piece D, is curved as seen in 50 the figure, for the purpose of fitting the horse, and is held laterally in place by having the strap A, pass between and beneath the crupper or caudal strap of the harness.

There is erected upon the part D', the 55 standard for supporting the lines. This

consists of a foot piece E, firmly riveted to the piece D', and a standard F, which screws into, the foot piece E, so that it can be changed for a longer or shorter one, at pleasure. The standard F, has two arms 60 G, G, curved inward and upward at their extremities, forming a loop or stirrup, in which the lines are intended to rest while the horse is in motion. The standard rises above the pieces G, G, to any desired height, 65 and may be pinioned off in any desired style. The whole of the standard may be plated or otherwise finished.

The nature of my invention consists in placing on the horse's rump an attachment, 70 constructed, arranged, and secured as described, so that the arms G, G, shall be directly over the tail. Said attachment is for the purpose of supporting the lines out of 75 the reach of the animal's tail, and thereby prevent its becoming entangled in the lines while driving.

I am aware that eyes, or rings, called turrets, secured in the saddle, or to the head gear, of the harness, for supporting, and 80 more especially for guiding, the lines are in very common use—but the construction, arrangement, and location would be of no avail in effecting the object of my invention: that is, to prevent the animal from 85 throwing his tail over the lines—such, therefore, I wish to be understood as not claiming, but confine myself strictly to the arms G G with turned up ends, for the purpose of keeping the lines from slipping off, and 90 to release them readily when required, when the same is used in combination with the other described parts of it, and for the purpose specified.

What I claim and desire to be secured by 95 Letters Patent, as a new article of manufacture, is—

An attachment, or line supporter, to be placed on a horse's rump, by securing it to the harness in the manner shown, or in any 100 equivalent way said attachment consisting of the adjustable strap A, pin and clasp B and C, cross piece D, adjustable standard F, and arms G G, the whole arranged and combined as herein described, and for the purpose set forth.

T. D. BROWN.
